ABSTRACT

A new *Verbena* plant particularly distinguished by a red
flower color with small white eyes, large flower size and good
resistance to powdery mildew, is disclosed.

1 Drawing Sheet

1

Genus and species: *Verbena* sp.
Varietal denomination: 'KLEVP14490'.

BACKGROUND OF THE NEW PLANT

The present invention comprises a new and distinct variety of *Verbena*, botanically known as *Verbena* sp., and hereinafter referred to by the variety name 'KLEVP14490'. 'KLEVP14490' originated from a cross-pollination conducted in September 2009 in Cobbitty, Australia between the proprietary female *Verbena* variety 'V975' (unpatented), and the proprietary male *Verbena* variety 'V980' (unpatented).

The seeds from the cross were sown and plants were grown for evaluation, where an individual plant designated 'KLEVP14490' was selected from the group of plants in Cobbitty, NSW, Australia in April 2010.

In April 2010, 'KLEVP14490' was first vegetatively propagated by vegetative cuttings in Cobbitty, NSW, Australia. 'KLEVP14490' was found to reproduce true to type in successive generations of asexual propagation via vegetative cuttings.

SUMMARY

The following are the most outstanding and distinguishing characteristics of this new variety when grown under normal horticultural practices in Cobbitty, Australia.

1. Red flower color with small white eyes;
2. Large flower size; and
3. Good resistance to powdery mildew.

DESCRIPTION OF THE PHOTOGRAPH

This new *Verbena* plant is illustrated by the accompanying photograph, which shows the plant grown in a pot. The photograph is of a three-month-old plant grown in Stuttgart, Germany in May 2014. The colors shown are as true as can be reasonably obtained by conventional photographic procedures.

DESCRIPTION OF THE NEW VARIETY

The following detailed descriptions set forth the distinctive characteristics of 'KLEVP14490'. The data which define

2

these characteristics were collected from asexual reproductions carried out in Cobbitty, Australia. Data was collected on three-month-old plants grown in a greenhouse in Cobbitty, Australia in February 2015. Color references are to The 5 R.H.S. Colour Chart of The Royal Horticultural Society of London (R.H.S.)(2005).

Classification:

Family.—Verbenaceae.

Botanical.—*Verbena* sp.

Common.—*Verbena*.

Designation.—'KLEVP14490'.

Parentage:

Female parent.—The proprietary female *verbena* variety 'V975' (unpatented).

Male parent.—The proprietary male *verbena* variety 'V980' (unpatented).

Plant:

Growth and branching habit.—Semi-upright.

Height (from top of soil).—30.0 cm.

Width (horizontal plant diameter).—30.0 cm.

Time to produce a finished flowering plant.—Approximately 8 weeks.

Time to initiate and develop roots.—3 weeks.

Root description.—White.

25 **Stems:**

Number of branches per plant.—More than 35.

Growth habit.—Semi-upright.

Length.—20.0 cm.

Diameter.—1.0 cm.

Internode length.—Approximately 2.0 cm.

Color.—RHS 130D.

Anthocyanin.—Absent.

Texture and appearance.—Pubescence, round.

30 **Leaves:**

Arrangement.—Opposite.

Immature and mature leaf.—Color: Upper surface: RHS 141A. Lower surface: RHS 141C.

Length.—2.5 cm.

Width.—1.5 cm.

Shape.—Lanceolate.
